UNITED STATES PATENT OFFICE.

EMERY LIBERTY, OF NEW YORK, N. Y.

TELLER'S WINDOW.

SPECIFICATION forming part of Letters Patent No. 774,190, dated November 8, 1904.

Application filed March 22, 1904. Serial No. 199,502. (No model.)

To all whom it may concern:

Be it known that I, EMERY LIBERTY, a citizen of the United States, residing in the borough of Manhattan, city of New York, county and State of New York, have invented certain new and useful Improvements in Tellers' Windows, of which the following is a specification.

The present invention relates to improvements in tellers' windows and means for opening, closing, and locking the same.

The objects of the invention are to provide a window which may be opened for the passage of parcels too large to be passed under the wicket and which will be automatically closed and which cannot be forced open from the outside.

Another object of the invention is to provide a window which will be locked when closed and in all positions of opening and which when partially opened cannot be opened to a greater extent except by the mechanism actuated by the teller.

Another object is to produce a device for accomplishing this purpose and which will be noiseless in operation.

I accomplish these objects by the mechanism illustrated in the accompanying drawings, in which—

Figure 1 is a front elevation, partly in section, of the window, the wicket, and the mechanism for operating the same. Fig. 2 is a vertical section taken on the lines 2 2 of Fig. 1. Fig. 3 is an enlarged horizontal section taken on the lines 3 3 of Fig. 1. Fig. 4 is a front elevation of the mechanism, partially in section. Fig. 5 is a sectional view of the same, taken on the lines 5 5 of Fig. 3; and Fig. 6 is a rear view of a portion of the actuating mechanism.

In all of the views like parts are designated by the same numbers of reference.

In carrying out my invention I provide a window-opening 1, having a frame 2, formed, preferably, of hollow members. Within the opening are guides 3, within which the wicket 4 slides. The wicket is formed of the usual grating and with downward side extensions 5, which pass through openings in the top of the counter 6, and are provided with racks 7 7.

The wicket 4 is free to slide vertically within the opening 1. It normally rests in the position shown in Fig. 1, with a sufficient space between the bottom of the wicket and the counter for the passage of small articles, such as are ordinarily exchanged between the teller and the persons outside of the counter. The wicket may be elevated by mechanism about to be described, so that the space between it and the counter will be sufficient for the passage of large parcels. The wicket sliding vertically in guides cannot be easily forced inward by pressure or a blow from the outside, as is the case with wickets that are hinged and opened inward, as is customary.

The mechanism for elevating the wicket 65 comprises two gear-wheels 8 8, journaled upon a frame 9 9', connecting the sides of the frame 2 2 and meshing with the racks 7. Upon the shafts 10 of the wheels 8 are smaller gears 11, and these gears are connected to the gears 80 8, so that the latter will be rotated by them. The gears 11 intermesh with the racks 12, carried by a sliding plate 13, which is connected through a chain or rod 14 to a pedal 15. By depressing the pedal 15 the plate 13, 75 and with it the racks 12, will descend, the pinions 11 and gears 8 will be rotated, and the wicket elevated. By meshing the racks 12 with the small pinions, transmitting motion from them to the large gears 8 and from there 80 to the racks 7, an amplified motion is secured, and the pedal will have to be depressed but a short distance to elevate the wicket to the full height. The wicket will descend, owing to its own weight, upon pressure being removed 85 from the pedal. The plate 13 is provided with dovetail guides 16, which engage within ways of similar shape formed within the plate 9', so that the plate 13 will be guided in its up-and-down movement and the racks 12 will 90 always be in mesh with the pinions 11.

In order that the wicket may be locked when lowered and cannot be raised except by actuation of the elevating mechanism, a locking device comprising dogs 17, pivoted to the 95 plate 9, is provided. These dogs have right-angled engaging ends 18, which engage with the teeth of small pinions 19, which latter are

in mesh with the gears 8. The dogs are normally engaged with the pinions by means of springs 20. Each dog is provided with an extension-pin 21, which engages with the sides 5 of a vertical slide or cam-plate 22, carried by the plate 13. This slide is formed with notches 23, within which the extension-pins 21 will engage in the position shown in Fig. 4. These notches are provided with inclined upper surfaces 24. (Illustrated in Fig. 6.) The journals of the pinions 19 are supported in slots 25, which slots are inclined, as shown, and each is drawn upon a circle the center of which is the point of pivoting of the gear 8. A spring 15 26 normally elevates the plate 13 and pedal.

As before stated, the pinions 11 are connected to the gears 8; but they are not connected directly, but through a mechanism which allows them to turn to a certain extent 20 independently. This lost-motion mechanism is constructed as follows: Upon the hub of each of the gears 8 is a pin 27, which will turn in the path of a pin 28, carried by the pinion 11. These pins are normally mutually 25 arranged, as illustrated in Fig. 4, in which they are separated a short distance. This permits a pinion 11 to rotate to a slight extent before imparting a motion to a gear 8, and permits the former to be rotated almost 30 an entire revolution in the opposite direction before rotating the latter. The racks 12 are preferably as long as the circumference of the pinions 11, so that the latter will be rotated once by the depression of the rack 12. 35 The operation of the locking mechanism is as follows: Upon the plate 13 being depressed by the pedal the pins 21, which normally rest within the slots 23 and cause the dogs to engage with the pinions 19 and prevent them and the gears 8 from turning, are 40 disengaged by being slid up upon the inclined portions 24 of the notches 23, as shown in Fig. 6, disengaging the points 18 of the dogs from engagement with the pinions 19. The 45 downward movement of the plate 13 will carry with it the racks 12 and will rotate the pinions 11. The pins 28, carried by the latter, are normally in the position shown in Fig. 4, so that they will not engage with the pins 50 27, which are carried by the gear-wheels 8, until the dogs 17 have entirely disengaged themselves from the pinions 19. The pedal continuing to be depressed the wicket will be raised until it reaches the extreme point of 55 upward movement. Upon pressure being relieved from the pedal the spring 26 will first raise the plate 13 to the extreme point of elevation, the pinions 11 freely turning in the backward direction without resistance. This 60 upward movement of the plate 13 will engage the pins 21, carried by the dogs 17 with the notches 23, and engage the dogs with the pinions 19. The wicket will be free to fall as the gears 8 turn freely upon their axles, the

axles of the pinions 19 will rise in the slots 65 25 and allow the teeth of the gears 19 to slide past the dogs, which act like pawls and ratchets, but with less noise. When the wicket has dropped to the lowermost point in its movement, the pinions 19 will still engage 70 with the dogs and with the gears 8 and the wicket will be firmly locked against elevation, so that if a person from the outside of the window should attempt to raise the latter before it is fully closed the reverse movement 75 will be imparted to the wheels 8 and cause the pinions 19 to drop to the lowermost point in the slots 25 and firmly lock them against rotation by engagement with the dogs 17.

The lock just described and consisting of 80 the dogs and pinions is ready to act at any point to protect the wicket from being elevated by means other than the mechanism described. This feature is one of great importance, as it prevents the wicket being opened 85 from its outside before it is fully closed.

As an additional means for elevating the wicket, a hand-crank 27, attached to a shaft 28' and carrying a pinion 29, may be employed. The pinion 29 intermeshes with a 90 rack 30, carried by the plate 13, a slot 31 in the latter permitting the shaft 28' to have a bearing upon both of the plates 9 and 9'. The crank 27 by being rotated will raise the plate 13 in the manner similar to the action 95 of the pedal.

Instead of the spring 26 connecting the plate 13 with the frame of the window a spiral spring 32 may be employed, which spring may be carried within a box or casing 33 and 100 will tend to rotate the shaft 28 and elevate the plate 13, and to assist the elevating mechanism counterweights 34, working within the posts 2, may be used, such counterweights connecting with the wicket by means of wires 105 or chains 35, which pass over guide-pulleys 36. These counterweights should not be sufficiently heavy as to appreciably retard the descent of the wicket, but will assist the elevation of heavy wickets. 110

The action of the pinions 19 upon the teeth of the gears 8 makes less noise than a pawl and ratchet, and for this reason they are preferred.

Ordinary wickets, such as I am familiar with, are hinged to the window, and are provided with a latch or lock, by means of which they are kept closed. Owing to the extreme width of counters now used in most banking-houses it is more or less difficult and frequently becomes irksome for the teller to close 115 the wicket every time after it has been opened. For this reason he is frequently tempted to keep the wicket unlatched, which is a very dangerous practice. By my invention the wicket being elevated by pressure of the foot 120 or by rotation of the handle will be automatically closed as soon as pressure is removed from either. Hence there will be no tempta- 125

tion on the part of the teller not to close the wicket. Should a person on the outside of the counter attempt to lift up the wicket while it is descending, his action will be prevented 5 by means of the dogs and pinions, as before described. The attention of the teller will be immediately attracted to this, as he at once sees that the wicket has not closed, and he will be in a position to take measures to insure safety.

Having thus described my invention, what I claim as new, and desire to secure by Letters Patent, is—

1. The combination with a window, of a wicket movable therein, means for locking the wicket against open movement irrespective of the position of the wicket, means for disengaging the lock and positively opening the wicket, means for closing the wicket, and means for locking the wicket against open movement during the closing movement, substantially as described.

2. The combination with a window, of a wicket slidably mounted therein, means for locking the wicket against open movement irrespective of the position of the wicket, manually controlled means for disengaging the locking means and positively elevating the wicket, means for locking the wicket against open movement during the closing movement, and means for automatically closing the wicket, substantially as described.

3. The combination with a counter and a window above the same, of a wicket sliding in guides within the window, and means for sliding the wicket, means for locking the wicket, such means operating to lock the wicket at any point against open movement during the closing movement, and means for automatically closing the wicket, substantially as described.

4. The combination with a window and a wicket sliding therein, of means for sliding the said wicket in an open direction, such means operating to slide the wicket in one direction only, means for locking the said wicket during the closing movement against open movement such means acting at any point of movement of the wicket and means for automatically closing the wicket, substantially as described.

5. The combination with a window, of a wicket sliding therein, means for sliding the said wicket in the open direction, such means operating to slide the wicket in one direction only, and means for locking the said wicket against open movement, such means acting at any point of the closing movement of the wicket, such means being actuated by the operating means, and means for automatically closing the wicket, substantially as described.

6. The combination with a window, of a wicket sliding therein, means for sliding the said wicket in the open direction, such means operating to slide the wicket in one direction

only and means for locking the said wicket against open movement, such means acting at any point of the closing movement of the wicket, and such means being independent of the wicket, and means for automatically closing the wicket, substantially as described.

7. The combination with a window, of a wicket sliding therein, means for elevating the wicket, such means operating in one direction only, and means for locking the said wicket against open movement, such means acting at any point of movement of the wicket, and means for automatically closing the wicket, substantially as described.

8. The combination with a window, of a wicket sliding therein, means for elevating the wicket, such means operating in one direction only, and means for locking the said wicket against open movement at any part of its closing movement, such means being actuated by the elevating means, substantially as described.

9. In a teller's window, the combination of a sliding wicket and means for sliding such wicket, such means being controlled by a pedal, and means for locking the said wicket against open movement at any point of its closing movement, such means being actuated by the sliding means, substantially as described.

10. The combination with a window, of a wicket therein, means for moving the said wicket, and means actuated by such moving means for locking and unlocking the wicket, the locking means acting at any point of the movement of the wicket, substantially as described.

11. In a teller's window, the combination of a sliding wicket, racks thereon, gears engaging therewith, a plate and sliding means for sliding the plate, and connections between the sliding plate and the gears, substantially as described.

12. In a teller's window, the combination of a sliding wicket, racks thereon, gears engaging therewith, a plate having racks thereon, pinions engaging with the racks, and connections between the pinions and gears, substantially as described.

13. In a teller's window, the combination of a sliding wicket, racks thereon, gears engaging therewith, a plate having racks thereon, pinions engaging with the racks, and connections between the pinions and gears, the said connections permitting lost movement so that the plate can move independently of the wicket, substantially as described.

14. In a teller's window, the combination of a sliding wicket, a sliding element, gearing between the element and the wicket, and a lock for preventing open movement of the wicket, substantially as described.

15. In a teller's window, the combination of a sliding wicket, a sliding element, racks carried by the element engaging with mechanism

for opening the wicket, and dogs engaging with the mechanism to prevent the opening of the wicket, substantially as described.

16. In a teller's window, the combination of 5 a sliding wicket, and means for opening and locking the same, such means comprising gear-wheels, pinions engaging therewith, the axles of the pinions working in slots, and dogs engaging with the pinions, substantially as de-
10 scribed.

17. In a teller's window, the combination of a sliding wicket, racks thereon, two gears 15 engaging with the racks, a sliding plate, racks thereon, two pinions engaging with such racks, and connections between the pinions and the gears, and means for moving the plate, substantially as described.

18. In a teller's window the combination of a sliding wicket, racks thereon, two gears en- 20 gaging with the same, two pinions, a sliding plate, racks thereon engaging with the pinions, connections between the pinions and the gears, additional pinions meshing with the gears, and dogs engaging with the pinions, 25 the axles of said pinions working in slots, substantially as described.

19. In a teller's window, the combination of a sliding wicket, a gear for elevating the same, a moving member, a pinion engaging there- 30 with, and lost-motion connections between the gear and pinion, substantially as described.

20. In a teller's window, the combination of a sliding wicket, gears for opening the same, a sliding member carrying means for rotating 35 the gears, dogs, and a cam-plate carried by the sliding member and engaging with the dogs, substantially as described.

21. In a teller's window, the combination of a sliding wicket and racks thereon, a gear en- 40 gaging therewith, a pinion connected to the gear with a lost-motion connection, a moving member, a rack thereon engaging with the pinion, and another pinion engaging with the gear, a dog engaging with the pinion, the axle 45 of the said pinion moving in a slot, and a cam-

plate carried by the moving member and en- gaging with the dog, substantially as de- scribed.

22. In a teller's window, the combination of a sliding wicket, two racks thereon, two gears 50 engaging therewith, a pinion engaging with each of the gears through a lost-motion connection, a sliding member carrying racks which engage with the pinion, additional pinions engaging with the gears, the axles of the 55 said pinions moving in slots, dogs engaging with the additional pinions, and a cam-plate carried by the moving member engaging with the dogs, substantially as described.

23. In a teller's window, the combination of a sliding wicket, a moving member, connec- 60 tions between the moving member and the wicket, a crank, a pinion thereon, a rack car- 65 ried by the moving member and engaging with the pinion, and a spring for actuating the pin- ion, substantially as described.

24. In a teller's window, the combination with a sliding wicket, of a moving member, means actuated by the teller for moving such member, connections between the member and 70 the wicket for opening the latter, means for moving the member independently of the wicket, the independent movement of the plate- 75 actuating means to prevent open moving of the wicket at any point, substantially as de- scribed.

25. In a teller's window, the combination of a sliding wicket, and means for sliding such wicket, such means including a plate gearing 80 between the wicket and plate, means for mov- ing the plate in one direction, and a spring for moving it in the other direction, substan- 85 tially as described.

This specification signed and witnessed this 15th day of March, 1904.
